UNITED STATES PATENT OFFICE.

WILLIAM E. PHILIPS, OF STREATOR, ILLINOIS, ASSIGNOR TO METAL STAMPINGS CORPORATION, OF STREATOR, ILLINOIS, A CORPORATION OF ILLINOIS.

DESIGN FOR A BICYCLE-FRAME.

45,156.

Specification for Design.

Patented Jan. 13, 1914.

Application filed April 2, 1913. Serial No. 758,496. Term of patent 14 years.

To all whom it may concern:

Be it known that I, WILLIAM E. PHILIPS, a citizen of the United States, residing at Streator, in the county of La Salle and State of Illinois, have invented a new, original, and ornamental Design for a Bicycle-Frame, of which the following is a specification, reference being had to the accompanying drawing, forming part thereof.

Figure 1 is a side elevation and Fig. 2 a

plan view of a bicycle frame showing my new design.

I claim:

The ornamental design for a bicycle frame as shown.

WILLIAM E. PHILIPS.
